UNITED STATES PATENT OFFICE.

ANTON SCHUH, OF VIENNA, AUSTRIA-HUNGARY.

CLAMPING DEVICE FOR WOODEN BOXES AND THE LIKE.

1,010,524.

Specification of Letters Patent.

Patented Dec. 5, 1911.

Application filed December 12, 1910. Serial No. 596,973.

To all whom it may concern:

Be it known that I, ANTON SCHUH, a subject of the Emperor of Austria-Hungary, and residing at 8 Getreidemarkt, Vienna, 5 Austria-Hungary, have invented new and useful Improvements in Clamping Devices for Wooden Boxes and the Like, of which the following is a specification.

The invention relates to clamping devices 10 for wooden boxes and the like, these devices consisting of a flat bridge piece preferably of sheet metal, together with two lateral shanks thereon, the object or purpose of these devices being to prevent any undue 15 opening of the boxes or the like without making at once visible any such effort.

It is the object of the present invention to make known at once every undue effort, tending to remove the clamping device from 20 the box and also to prevent absolutely any reinserting of the clamp into the box.

It is a further object of this invention to enable the manufacture of the clamp in a most economical way.

25 The drawings illustrate two modes of execution of my invention.

Figure 1 shows a clamp in a perspective view, Fig. 2 the same in sectional elevation inserted into a box fixed thereto with a nail, 30 and Fig. 3 shows an alternative mode of execution of the clamp.

a is a bridge piece of the clamp and *b*—*b*¹ are the shanks projecting therefrom, these shanks being preferably pointed or sharpened at their ends. It is an essential feature 35 of the present invention, that the shanks *b*—*b*¹ are stamped out from the material forming the said bridge of the clamp and it is readily to be seen, that thereby a very 40 economical manufacture of the clamp is insured. Furthermore, since the crosspieces *c*—*c*¹, remaining at the borders of the bridge-piece after stamping are very narrow, it will be readily understood, that every effort tend- 45 ing to remove the clamp from the box causes an immediate tearing of the said crosspieces.

It is preferable to protect the borders of the bridge piece against injuries as shocks. In order to obtain such protection it has been 50 found advantageous to insert the bridge piece of the clamp into the wall of the box in

such a manner that no edge of the clamp projects beyond the wall of the box and this insertion is preferably performed when the clamp is driven into the box. The same purpose may be attained by bending inwardly 55 the four edges of the bridge piece, these bent edges cutting therefore into the wood if driven in. Fig. 3 of the drawing shows a clamp, the edges *d* thereof being bent in accordance and to the purpose before described. 60

Having now described the nature of my invention, what I claim is:

1. In combination with two abutting pieces of material, of a bridge piece comprising 65 a flat, straight body portion extending across and lying abreast of the juncture of said pieces, said body portion having shanks stamped out from portions thereof lying wholly within the margins of said body and 70 the shanks comprising more than half of the material of the body portion to materially weaken the same, and a nail or the like extending through said pieces and shanks and lying parallel with said body portion, sub- 75 stantially as described.

2. In combination with two abutting pieces of material, of a bridge piece comprising a flat, straight body portion extending across and lying abreast of the juncture of said 80 pieces, said body portion having shanks stamped out from portions lying wholly within the margins of said body with the bases of the shanks near the ends of said body and the ends of the shanks being 85 formed of portions near the center of said body thereby forming a relatively narrow central connecting bridge piece for the body and relatively narrow end connecting bridge pieces for said body, said stamped out portion comprising more than half of the material of the body portion to thereby weaken the same, and a nail or the like extending through said abutting pieces and shanks and lying parallel to said body portion, substan- 90 tially as described.

In testimony whereof I affix my signature in presence of two witnesses.

ANTON SCHUH.
